FUEL DISTRIBUTING MEANS

Eugene Martin, Erie, Pa., assignor to The Standard Stoker Company, Incorporated, a corporation of Delaware

Application September 25, 1940, Serial No. 358,269

11 Claims. (Cl. 110—105.6)

This invention relates to stokers and particularly to a stoker of the type in which the fuel discharge conduit extends upwardly through the central portion of the firebox grate and in which the fuel is projected in aerial paths over all parts of the fuel bed.

An object of the invention is to provide a stoker of this type in which the fuel is positively conveyed from a source of supply to a point of distribution above the firebox grates and centrally of the firebox.

Another object of the invention is to provide a novel fuel projecting and distributing means for a stoker of the above type, that is simple in construction, efficient in operation, requires a minimum of mechanism and takes up a minimum of space.

More specifically, an object of the invention is to provide a novel combined fuel elevating conveyor screw and fuel distributing jet member.

The firebox of a locomotive in horizontal cross section just above the grate is substantially rectangular in shape and is longer than it is wide. With the fuel projecting means disposed centrally of the firebox, it is apparent that a greater force is required to project fuel to the extreme side central portions thereof; and a greater force is required to project fuel to the four extreme corner portions of the firebed than to the front and rear central portions thereof. It is, therefore, another object of the invention to incorporate with a stoker of the above type, a fuel projecting means for distributing fuel successively to all parts of the firebed and means automatically controlling the force with which the fuel is projected to the various parts of the firebed in accordance with the distance from the projecting means to the various parts of the firebed.

More specifically, it is an object of the invention to provide in a stoker delivering fuel to a point above the firebed and centrally of the firebox, a pressure fluid jet head rotatable about a vertical axis, arranged to emit a blast of fluid under pressure for successively projecting fuel to all parts of the firebed, and means for automatically varying the intensity of said blast as the jet head rotates.

These and other objects of the invention, residing in the construction, arrangement and combination of the various parts of the apparatus, will become apparent from the following description when read in connection with the accompanying drawings, in which

Fig. 1 is a central, vertical, longitudinal sec- 55 box 11 to cause air to be drawn into the firebox

tion through a locomotive firebox showing the invention partly in similar section and partly in elevation;

5 Fig. 2 is a sectional view taken on line 2—2 of Fig. 1;

Fig. 3 is a sectional view taken on line 3—3 of Fig. 2; and

Fig. 4 is a fragmentary sectional view taken on the line 4—4 of Fig. 2.

10 The invention has been illustrated and will be described as applied to the firebox of a locomotive to which it is particularly adaptable, it is apparent, however, that the invention may be used to advantage in other fireboxes.

15 On the drawings, the letter L indicates a locomotive which includes the boiler 10 and firebox 11. The boiler 10 has a hollow back wall 12, a hollow front wall 13 and hollow side walls (not shown), which together with the grates 14 define the firebox 11. The hollow back wall 12 is provided with the conventional firing opening 15 and the power operated firedoor 16 forms a closure therefor.

20 The boiler 10 is supported in any suitable manner on the locomotive underframe 17. The grates 14 of the locomotive firebox are, in the present construction, arranged in three rows extending longitudinally and spaced transversely of the firebox. The outer ends of the center row of 25 grates 14 are supported in bearer bars, such as 18, which also serve to support the inner ends of the side grate sections 14. The outer ends of the side grate sections are supported in a well known manner (not shown) along the lower side 30 portions of the mud ring 19, which supports the firebox 11. An ash pan 20 is disposed beneath the grates 14 and is arranged so that its outlets 21 and 22 pass through the locomotive underframe 17.

35 40 Extending rearwardly and upwardly from the lower portion of the hollow front wall 13 to the upper portion of the hollow back wall 12 are a plurality of water circulating transversely spaced tubes 23 arranged to support a refractory brick arch 24. The arch 24 at its lower forward end is sealed against the front wall 13 while at its upper rearward end terminates short of the back wall 12 to provide an opening 25 which extends along the rear portion of the back wall 12,

45 50 through which opening products of combustion pass on their way to the flues 26 and the locomotive stack. Drafting of the firebox is accomplished in known manner consisting in producing a sub-atmospheric pressure within the firebox 11 to cause air to be drawn into the firebox

through the ash pan 20 and thence through and between the grates 14.

The stoker for feeding coal from the tender (not shown) is indicated generally by the letter S and includes a tubular horizontally disposed conduit 27 extending along the longitudinal center line of the locomotive beneath the locomotive cab deck 28, mud ring 19 and grates 14. The stoker also includes a vertical tubular conduit 29, disposed substantially midway between the hollow front wall 13 and hollow back wall 12, and between the grate bearer bars 18. The conduit 29 comprises the tubular conduit portion 30 of a cast member 36 and a cylindrical casing 31 received in a seat 32 formed in the upper end of the tubular conduit portion 30. The conduit 29 extends above and below the grates 14, communicating, through the lateral opening 33 in the tubular conduit portion 30, with the forward end of the horizontal conduit 27.

The cast member 36 is rigidly supported on the locomotive underframe 17 in any suitable manner, as by the brackets 41 and 42. The tubular conduit portion 30 is provided with a spherical split flange 34 embracing the opening 33, the flange 34 being arranged to receive the spherical sleeve 35, in which sleeve is slidably mounted the forward end of the conduit 27. The whole forms a ball joint providing for universal and longitudinal movement between the conduits 27 and 29.

The lower portion of the cast member 36, beneath the tubular conduit portion 30, is formed to provide a gear housing 37. At its lower end, the gear housing 37 is open, and a removable cover 38, suitably secured to the housing 37, forms a closure therefor. A hollow vertical shaft 43 extends through the gear housing 37 into the lower end of the tubular conduit portion 30, and is mounted for rotation in roller bearings 39 and 40 in the cover 38 and gear housing 37, respectively.

A screw conveyor 44 is disposed in the vertical tubular conduit 29 and is rigidly secured to the upper end of the vertical shaft 43 by means of the threaded bolts 45 passing through the abutting flanges 46 and 47 of the screw conveyor 44 and vertical shaft 43, respectively. A screw conveyor 48, disposed in the conduit 27, carries the fuel forwardly from the tender to the base of the vertical screw conveyor 44.

The screw conveyors 44 and 48 are both operated by the two cylinder reciprocating steam engine 49, though obviously any other suitable means may be employed. The screw conveyor 48 is driven from its rearward end through suitable shafting and reduction gearing (not shown) in a manner well known to those versed in the art. The mechanism for driving the vertical screw conveyor includes, a gear 50 secured on the vertical shaft 43, the gear 50 meshing with worm 51, and the worm 51 being operatively connected with the engine 49 by a drive shaft 52.

The cylindrical casing 31 of the tubular conduit 29 is provided at its upper end with an annular flange 53 upon which is seated the firing table 54, the upper surface of which is flat and substantially in a horizontal plane. Protective grates 55 extend between the firing table 54 and the grates 14 and embrace the cylindrical casing 31, protecting the latter from the heat of the firebox.

The conveyor screw 44 is provided with a hub 56 having a passage 57 therein communicating

10 endwise at its lower end with the passage 58 of the hollow shaft 43. At the upper end of the screw flight of the screw conveyor 44 there is formed a vertically extending jet head 59 projecting radially from the hub 56. The jet head 59 is provided with a chamber 60 communicating with the passage 57 and a plurality of horizontally aligned jet apertures 61 in the vertical face 62 of the jet head communicating with the chamber 60.

15 The passage 58 of the hollow shaft 43 communicates at its lower end with a pressure fluid supply line 63. The supply line 63 leads from a suitable source of fluid under pressure, preferably steam, and a valve (not shown) in the supply line can be adjusted to deliver the steam at a predetermined pressure. The fluid under pressure thus passes from the supply line 63 through the passage 58, thence through the passage 51 in the hub 56 of the vertical screw 44 into the chamber 60, from which chamber the fluid is emitted under pressure through the jet apertures 61. The pressure fluid emitted from the jet apertures 61 projects the fuel elevated by the vertical screw 44 across the table 54 successively to all parts of the firebox 11.

20 The firebox of a locomotive is generally rectangular in shape and is greater in length than in width. All points on the perimeter of the firebox are therefore not equidistant from the central point of projection of the fuel. Provision has been made for automatically varying the pressure of the fluid in accordance with the distance the fuel is desired to be projected. The extreme front and rear central areas of the firebox are farther removed from the jet head 59 than the extreme lateral central areas and therefore greater fluid pressure is required to project the fuel to the extreme front and rear central areas than to the extreme lateral central areas. Similarly greater pressure is required to project the fuel to the four corner portions of the firebox, since these are still farther removed from the jet head 59.

25 In order to provide for the increased fluid pressure, a booster supply line 64 communicates with the normal supply line 63. A valve 65 is interposed in the booster supply line 64 and is provided with a restricted passage 66. The extent of the opening in the passage 66 is controlled by a valve member 67, the stem 68 of which projects into the gear housing 37. The end of the stem 68 within the housing 37 is provided with a stud or crosshead 69 and a compressed spring 70 around the stem 68 between the crosshead 69 and the inner wall of the gear housing 37 normally moves the valve member 67 away from the passage 66. The gear 50 is provided on its under side with a cam 71 arranged to engage the roller 72 which is carried by the crosshead 69. Thus, as the cam 71 rotates, the valve member is moved in and out of the passage 66 whereby varying amounts of fluid is permitted to pass therethrough into the supply line 63 to vary the pressure of the fluid delivered to the jet head 59.

30 The shape of the cam 71 is such that the passage 66 will be fully open when the jet apertures 61 are directed to the four corner portions of the firebox; partly open when the jet apertures 61 are directed toward the lateral central portions of the firebox. It will be seen from the above that the pressure of the blast is automatically varied in accordance with the distance

that the fuel has to be projected to reach the various portions of the perimeter of the firebox.

I claim:

1. In a firebox having a grate, the combination of a fuel discharge conduit extending upwardly through the central portion and above the level of said grate into the firebox, a screw conveyor in said conduit for urging fuel therethrough to the firebox, said screw conveyor having a hollow hub in communication with a source of fluid under pressure, a chambered jet head at the delivery end of said discharge conduit communicating with said hollow hub of said screw conveyor, said chambered jet head being provided with jet openings for the emission of fluid under pressure for projecting over the firebox grate all the fuel delivered by said screw conveyor, and means for rotating said screw conveyor and jet head.

2. In a firebox having a grate, the combination of a fuel discharge conduit extending upwardly through the central portion and above the level of said grate into the firebox, a screw conveyor in said conduit for urging fuel therethrough to the firebox, said screw conveyor having a hollow hub, means for rotating said screw conveyor including a hollow shaft in endwise relation with said screw conveyor providing a continuous passage through said shaft and hub, a chambered jet head at the delivery end of said discharge conduit communicating with said hollow hub of said screw conveyor, said hollow shaft being in communication with a source of fluid under pressure, and said chambered jet head being provided with jet openings for the emission of fluid under pressure for projecting over the firebox grate all the fuel delivered by said screw conveyor.

3. In a firebox having a grate, the combination of a conduit leading from a source of fuel and communicating with said firebox, a screw conveyor in said conduit for conveying fuel to the firebox, said screw conveyor having a hollow hub in communication with a source of fluid under pressure, a chambered jet head at the delivery end of said screw conveyor communicating with said hollow hub, said chambered jet head being provided with jet openings for the emission of fluid under pressure for projecting the fuel delivered by said screw conveyor over the firebox grate, means for rotating said screw conveyor and jet head, and means for automatically increasing and decreasing the pressure of said fluid in direct proportion as the axial distance from said jet openings to the marginal edge of said grate increases and decreases during rotation of said screw conveyor.

4. In a firebox having a grate, the combination of a fuel discharge conduit extending upwardly through said grate into the firebox, said screw conveyor having a hollow hub in communication with a source of fluid under pressure, a chambered jet head at the delivery end of said screw conveyor communicating with said hollow hub, said chambered jet head being provided with jet openings for the emission of fluid under pressure for projecting the fuel delivered by said screw conveyor over the firebox grate, means for rotating said screw conveyor and jet head, and means for automatically increasing and decreasing the pressure of said fluid in direct proportion as the axial distance from said jet openings to the marginal edge of said grate increases and decreases during rotation of said screw conveyor.

5. In a firebox having a grate, the combination of a fuel discharge conduit extending upwardly through the central portion of said grate into the

firebox, said screw conveyor having a hollow hub in communication with a source of fluid under pressure, a chambered jet head at the delivery end of said screw conveyor communicating with said hollow hub, said chambered jet head being provided with jet openings for the emission of fluid under pressure for projecting the fuel delivered by said screw conveyor over the firebox grate, means for rotating said screw conveyor and jet head, and means for automatically increasing and decreasing the pressure of said fluid in direct proportion as the axial distance from said jet openings to the marginal edge of said grate increases and decreases during rotation of said screw conveyor.

6. In a firebox having a grate, the combination of a fuel discharge conduit extending upwardly through said grate into the firebox, a screw conveyor in said conduit for conveying fuel to the firebox, said screw conveyor having a hollow hub, means for rotating said screw conveyor including a hollow shaft in endwise relation with said screw conveyor providing a continuous passage through said shaft and hub, a chambered jet head formed with the delivery end of said screw conveyor and communicating with said hollow hub, said chambered jet head being provided with jet openings, a pressure fluid supply line communicating with said passage supplying fluid under pressure to said jet head for emission from said jet openings for projecting the fuel delivered by said screw conveyor over the firebox grate, a booster pressure fluid supply line communicating with said first named supply line, a valve in said booster line, and a cam mounted to rotate with said hollow shaft, said valve being responsive to said cam for varying the amount of fluid under pressure delivered from said booster line to said first named supply line.

7. In a firebox having a grate, the combination of a fuel discharge conduit extending upwardly through said grate into the firebox, a screw conveyor in said conduit for conveying fuel to the firebox, said screw conveyor having a hollow hub, means for rotating said screw conveyor including a hollow shaft in endwise relation with said screw conveyor providing a continuous passage through said shaft and hub, a chambered jet head formed with the delivery end of said screw conveyor and communicating with said hollow hub, said chambered jet head being provided with jet openings, a pressure fluid supply line communicating with said passage supplying fluid under pressure to said jet head for emission from said jet openings for projecting the fuel delivered by said screw conveyor over the firebox grate, a booster pressure fluid supply line communicating with said first named supply line, a valve in said booster line, and a cam mounted to rotate with said hollow shaft, said valve being responsive to said cam for varying the amount of fluid under pressure delivered from said booster line to said first named supply line, said cam being configured to increase and decrease the pressure of the fluid in said first named supply line in direct proportion as the axial distance from said jet openings to the marginal edge of said grate increases and decreases during rotation of said screw conveyor.

8. As an article of manufacture a screw conveyor having a hollow hub and a chambered jet head at the delivery end of said screw conveyor communicating with said hollow hub, said jet head extending radially from said hub and forming a continuation of said screw flight, said jet head being provided with jet openings.

9. As an article of manufacture a screw conveyor having a hollow hub and a chambered jet head at the delivery end of said screw conveyor communicating with said hollow hub, said jet head extending radially from said hub and forming a continuation of said screw flight, said jet head being provided with jet openings, the axes of said jet openings being substantially at right angles with respect to the axis of said hollow hub.

10. As an article of manufacture a screw conveyor having a hollow hub and a chambered jet head at the delivery end of said screw conveyor communicating with said hollow hub, said jet head extending radially from said hub and hav-

ing a face lying in a plane substantially parallel with the axis of said hollow hub, said face being provided with a plurality of jet openings.

11. In combination with a firebox having a grate, a stoker fuel discharge conduit extending upwardly through the central portion of said grate and terminating in said firebox above the level of said grate, a screw conveyor in said discharge conduit for conveying fuel therethrough and fuel distributing means at the upper end of said discharge conduit arranged to rotate with said screw conveyor for projecting fuel radially over all parts of said grate.
